(57) **CLAIM**

The ornamental design for an analyte monitoring device, as shown and described.

DESCRIPTION

FIG. 1 is a top perspective view of an analyte monitoring device, showing our new design.

FIG. 2 is a bottom perspective view thereof.

FIG. 3 is a top plan view thereof.

FIG. 4 is a bottom plan view thereof.

FIG. 5 is a right-side elevational view thereof. The left-side elevational view is a mirror image thereof.

FIG. 6 is a front elevational view thereof. The rear elevational view is identical.

FIG. 7 is a bottom perspective view thereof with unclaimed features removed; and,

FIG. 8 is a bottom plan view thereof with the unclaimed features removed.

The broken lines in the drawings illustrate portions of the analyte monitoring device that form no part of the claimed design.
